UNITED STATES PATENT OFFICE

HERALD B. GREENING, OF HAMILTON, ONTARIO, CANADA, AND JAMES W. GALLOWAY, OF DETROIT, MICHIGAN, ASSIGNEES TO GALLOWAY ENGINEERING COMPANY, LIMITED, OF HAMILTON, ONTARIO, CANADA

TWO CYCLE INTERNAL COMBUSTION ENGINE SWASH PLATE CONSTRUCTION

Application filed January 14, 1929. Serial No. 332,385.

The principal objects of the invention are to produce an extremely compact form of engine in which the weight and bulk per horse power will be materially reduced from 5 the ordinary type of crank shaft engine, to devise an engine which will have a very uniform torque, which will be particularly adapted for aeroplane service and will present an extremely small frontal resistance 10 area.

A further and important object is to facilitate the application of the two-cycle type of engine to a construction in which the torque is applied to the shaft through a "swash 15 plate."

The principal feature of the invention consists in the novel arrangement of a plurality of cylinders parallelly disposed around the engine shaft, said cylinders having their 20 head ends connected in pairs, one cylinder of each pair having an intake port and the other cylinder of each pair having an exhaust port, the pistons operating in said cylinders being operatively connected with a swash plate 25 mounted on the shaft.

In the accompanying drawings, Figure 1 is a longitudinal sectional elevation of an engine constructed in accordance with this invention taken through the line 1-1 of 30 Figure 2.

Figure 2 is an end elevation and part sectional view taken on the line 2-2-2 of Figure 1.

Figure 3 is a sectional detail illustrating 35 the paired arrangement of the cylinders and common combustion head.

In reference to the accompanying drawings the casing 1 is of substantially cylinder 40 form and has extending from one end thereof a plurality of cylinders 2-3 which are arranged in pairs, said pairs being equally spaced and arranged with their axes parallel with the axis of the casing.

Each of the cylinders 2 is provided with a 45 port 4 and the ports 4 of the group of cylinders are connected to a suitable manifold.

Each of the cylinders 3 is provided with a port 5 and the ports 5 of the group of cylinders are connected to a suitable manifold.

These manifolds are not shown as they may be arranged in various forms.

The outer ends of each pair of cylinders 2-3 are connected together by a cap 6 which is formed with a recess 7 in the underside 55 which forms a common combustion chamber for a pair of cylinders.

The arrangement of paired two cycle cylinders with a common combustion head is known to the art and further description 60 thereof is not considered necessary.

Within each of the cylinders 2-3 is arranged a piston 8 and to each piston is secured a rod 9 connecting the piston with a cross-head 10 which is slidably mounted in 65 the casing 1.

A shaft 11 is mounted in a suitable bearing 12 arranged in the casing head 13 and the other end is supported in a bearing 14 mounted in the head 15 which supports the outer ends of the cylinders 2-3. 70

A swash plate 16 is rigidly secured to the shaft 11 within the casing 1 and operatively engages the several bearing blocks 17 carried by the cross-head 10. 75

It will be readily understood that owing to the angularity of the swash plate, one of the pistons of each pair of cylinders 2-3 will have a slight lead over the other piston of each pair and the cylinders in which the leading pistons are arranged will have their ports connected with the exhaust manifold while the ports of the other cylinders will be connected to an intake manifold. 80

It will be understood that this peculiar arrangement of leads of the pistons in the exhaust cylinders will effect the opening of the exhaust port of each pair in advance of the opening of the intake port so that the cylinder pressure will be reduced practically to atmosphere before the intake port in the adjacent cylinder of the pair is opened. 85

It will be preferable to feed the inflowing charge of carburetted air under pressure and this will force the products of combustion in the intake cylinder outwardly through the common combustion head into the exhaust cylinder and owing to the lead of the pistons in the exhaust cylinders, the intake ports will remain open until after the exhaust ports 90 95 100

are closed. This will ensure a full charge of carburetted air to both cylinders.

On the closing of the intake ports, both pistons will compress the charge into the common combustion chamber and upon the firing of the charge the pistons will reverse their movement and exert their longitudinal thrust against the swash plate to rotate the shaft.

10 It will be understood that with an arrangement of a plurality of paired cylinders such as described arranged around the shaft, a uniform torque will be applied through the swash plate to the shaft.

15 It will be obvious that any desirable number of pairs of cylinders may be arranged around the shaft and if desired a duplicate set of cylinders may be arranged at the opposite end of the casing 1 to work in co-operation with the other set of cylinders so that thrust may be applied to the swash plate in both directions.

What we claim as our invention is:

An internal combustion engine, comprising a casing having a plurality of pairs of cylinders extending from the end thereof parallel with the axis of the casing, the cylinders of each of said pairs being connected by a common combustion head, one cylinder of each pair having an intake port and the other cylinder of each pair having an exhaust port, a shaft axially mounted in said casing, a swash plate rigidly secured to said shaft, pistons operating in said cylinders, and cross-heads slidably arranged in said casing and connected with said pistons an operatively engaging the angled surfaces of said swash plate.
